New York, N. Y., a corporation of New York

Application May 1, 1935, Serial No. 19,149

8 Claims. (Cl. 171—312)

This invention relates to power supply circuits and more particularly to power circuits for supplying constant potential to space discharge devices.

5 One object of the invention is to provide a power circuit that shall have a potentiometer shunted across a gas-filled space discharge device for supplying power to load circuits and that shall have improved means for controlling the 10 operation of the space discharge device.

Another object of the invention is to provide a power circuit comprising a potentiometer shunted by a space discharge device and connected in series with a fixed resistance to a variable voltage 15 source for supplying constant potential to vacuum tubes that shall have improved means for triggering off the space discharge device and for controlling the potentiometer in case of failure of the device.

20 A further object of the invention is to provide a power supply circuit for vacuum tubes that shall have a gas-filled space discharge device connected to a variable voltage source in series with a fixed resistance and in parallel to a potentiometer, that shall temporarily raise the voltage impressed on the device to break it down and that shall insert resistance in series with said potentiometer in case of failure of the device.

It is well known that a mercury vapor or a gas- 30 filled space discharge device has a constant potential drop across its discharge path when in operation. The current flow through the device will vary according to the potential impressed on the electrodes of the device, but the voltage drop 35 across the discharge path in the device will remain constant. This characteristic of mercury vapor or gas-filled space discharge devices may be utilized for supplying constant potential to a load circuit. If a gas-filled space discharge device is connected in parallel to a potentiometer and in series with a fixed resistance to a variable voltage source a constant potential will be impressed across the potentiometer. The potentiometer may be employed as a source of constant 40 potential for space discharge devices.

In a mercury vapor device the same as in a gas-filled device having cold electrodes the striking voltage necessary to start a discharge is much 50 higher than the voltage required to sustain a discharge after it has been started. In the present invention means are provided for triggering off a gas-filled tube by a voltage raised only a small amount above the sustaining voltage. Moreover, 55 emergency means are provided for approximately

supplying constant voltage to a load circuit in case of failure of the space discharge device.

In the power supply circuit employed to illustrate the invention a potentiometer is connected in parallel to a gas-filled space discharge device 5 and in series with a fixed resistance to a variable voltage supply circuit which may be a telegraph battery. The potentiometer may supply potential to any suitable circuits such, for example, as the grid circuits of vacuum tubes employed in telegraph circuits. The gas-filled space discharge device which is connected in parallel to the potentiometer preferably has three cold electrodes and is filled with gas preferably in the helium group. Two of the electrodes in the gas-filled device are 15 employed for triggering off purposes to start a discharge. The third electrode in combination with one of the other electrodes serves to provide a discharge path having a constant voltage after a break-down of the device.

20 A single figure in the accompanying drawing is a diagrammatic view of a power circuit constructed in accordance with the invention.

Referring to the drawing a potentiometer 1 is shown connected in parallel circuit to a gas-filled 25 space discharge device 2 and in series with a main resistance 3 to a grounded variable voltage source 4. The main resistance which is connected in series with the variable voltage source 4 absorbs 30 variations in voltage of the source so that constant potential is impressed across the potentiometer. The gas-filled space discharge device 2 has a constant potential drop so that irrespective of the voltage impressed on it the voltage drop 35 through it will be the same. However, the current flow through the device varies in accordance with the potential of the source. The main resistance has a potential drop according to the variations of current flow through the gas-filled 40 space discharge device so that a constant voltage is impressed across the potentiometer. In the shunt circuit of the potentiometer around the device 2 are included a relay 5, a control resistance 6 and an adjustable resistance 7. The adjustable 45 resistance 7 included in the potentiometer circuit around the gas-filled device 2 serves to adjust the potential maintained across the potentiometer and to adjust the voltage impressed on the electrodes of the space discharge device 2. The relay 5 is provided with an armature 8 for controlling 50 an alarm 9 and an armature 10 for controlling a protective resistance 11. A relay 12 having two armatures 13 and 14 is connected in circuit with the gas-filled space discharge device 2. The armature 13 of the relay 12 serves to short-circuit 55

the control resistance 6 when the relay is in operative position. The armature 14 of the relay 12 serves to complete a circuit for operating an alarm 15 when the relay is in released position.

5 The gas-filled space discharge device 2 is provided with three cold electrodes 16, 17, and 18. The electrodes 16 and 17 are located relatively close together and serve to trigger off the device. The electrode 18 is disposed further away 10 from the electrode 17 than the electrode 16 and serves to form a discharge path after triggering off between the electrodes 16 and 17. The sustained voltage between the electrodes 17 and 18 is steady whereas the sustained voltage between the electrodes 16 and 17 would not be substantially constant. A resistance 19 is provided between the electrodes 16 and 18 to permit discharge or triggering off between the electrodes 16 and 17 and to insure a majority of current passing between the electrodes 17 and 18 after breakdown of the 15 device.

In the drawing the potentiometer 1 is illustrated as the source of potential for the grids of vacuum tubes 20. It is, of course, apparent that the 20 potentiometer 1 may be employed as a source of potential for other types of load circuits. It is also apparent that the load circuits may be directly connected across the gas-filled space discharge device 2 if so desired. Voltmeter 21 is provided for indicating the voltage drop across the potentiometer 1.

Assuming the relays 5 and 12 are in released position and potential is supplied to the circuit from the battery 4, the control resistance 6 will 25 be in circuit with the potentiometer 1 and will insure sufficient voltage being impressed across the electrodes 16 and 17 of the device 2 to trigger off the device. The voltage impressed across the electrodes 16 and 17 in one form of the device may 30 be of the order of 75 to 95 volts. Upon breakdown of the device 2 a discharge path is formed between the electrodes 17 and 18. A potential of the order of 208 volts would be necessary to break the device between the electrodes 17 and 18. The 35 relay 12 is operated for short-circuiting the control resistance 6 so as to reduce the voltage impressed on the space discharge device 2. The short circuiting of the control resistance 6 also insures correct voltage being impressed across the 40 potentiometer 1. At this time the relay 5 is operated for short-circuiting the protective resistance 11 so that the discharge device 2 may operate to maintain substantially constant voltage drop across the potentiometer 1. The protective resistance 11 connected between the second and third electrodes of the gas-filled device 2 serves to permit triggering off of the gas-filled device 45 and after a breakdown of the device permits a majority of the current to discharge across the first and third electrodes. The relay 12, as before set forth is assumed to have a negligible resistance value.

In case of failure of the space discharge device 2, the relay 12 would be released. The armature 14 would complete a circuit for operating the alarm 15 in case of failure of the device 2. At the same time an armature 13 would remove the short circuit around the control resistance 6 so as to approximately maintain normal voltage drop 50 across the potentiometer 1. In case of failure of the circuit through the potentiometer the relay 5 will be released to complete a circuit for operating an alarm 9.

Modifications in the circuit and in the arrangement and location of parts may be made within 55

the spirit and scope of the invention and such modifications are intended to be covered by the appended claims.

What is claimed is:

1. In combination, a variable source of potential, a main resistance, a gas-filled space discharge device having cold electrodes connected to said source in series with said main resistance, a potentiometer connected in shunt circuit to said device, and means comprising a relay connected in 10 circuit with said device for increasing the potential across the device to break it down and for reducing the potential impressed on the device after breakdown has occurred to maintain constant voltage across said potentiometer. 15

2. In combination, a variable source of potential, a main resistance, a gas-filled space discharge device connected to said source in series with said main resistance, said device having three cold electrodes, a potentiometer connected in shunt circuit to said device, and means for increasing the potential across two electrodes of said device to trigger off the device and effect a conducting path including the third electrode and one of the first electrodes and for reducing the potential impressed on the device when the device has broken down to maintain constant voltage across said potentiometer. 20 25

3. In combination, a variable source of potential, a main resistance, a gas-filled space discharge device connected to said source in series with said main resistance, said device having three cold electrodes, a potentiometer connected in shunt circuit to said device, and means for triggering off said device by a path including two electrodes located relatively close together, for effecting a path including the third electrode and one of the first electrodes when the tube is broken down to maintain constant voltage across said potentiometer, and for inserting resistance in series with said 35 potentiometer in case of failure of said device to effect substantially normal voltage drop across the potentiometer. 40

4. In combination, a variable source of potential, a main resistance, a gas-filled space discharge device having three cold electrodes and connected to said source in series with said main resistance, a control resistance and a potentiometer connected to said source in series with the main resistance and in parallel circuit to said 45 device, and means comprising a relay connected in series with said device for governing said control resistance to trigger off said device by a path including two of said electrodes, said relay when in operative position completing a 50 short circuit around said control resistance. 55

5. In combination, a variable source of potential, a main resistance, a gas-filled space discharge device connected to said source in series with said main resistance, a potentiometer connected in parallel circuit to said tube and in series with said main resistance and said source, a control resistance and means comprising a relay having the operating coil thereof in series with said device for effectively connecting said control 65 resistance in series with said potentiometer to trigger off said device upon starting and to maintain substantially normal voltage across said potentiometer in case of failure of said device and for effectively short-circuiting said control resistance upon operation of said device. 70

6. In combination, a variable source of potential, a main resistance, a gas-filled space discharge device connected to said source in series with said main resistance, said device having 75

2,045,428

5 three cold electrodes, a potentiometer and a control resistance connected in parallel circuit to said device and in series with the main resistance and the source, a relay having the energizing coil thereof connected in series with a protective resistance and said device for governing said control resistance, a relay having the operating coil thereof connected in circuit with said potentiometer for controlling said protective resistance, and 10 a permanent resistance connecting two electrodes of said device.

15 7. In combination, a variable source of potential, a main resistance, a control resistance, a protective resistance, a potentiometer, a gas-filled space discharge device connected to said source in series with said main resistance, said device having three cold electrodes, a relay for governing said control resistance, the operating coil of said relay being connected in series with 20 said protective resistance and said device, said relay in released position effectively connecting said control resistance in series with the potentiometer to impress a breakdown potential on said device and operating upon breakdown of the 25 device to short-circuit the control resistance, and a second relay connected in series with said

potentiometer for short-circuiting said protective resistance to insure constant potential across the potentiometer.

8. In combination, a grounded variable source of potential, a main resistance, a potentiometer, 5 a relay, a protective resistance, a gas-filled space discharge device having three cold electrodes, one of said electrodes being connected in series with said main resistance to said source, a second electrode of said device located relatively close 10 to said first electrode to form a triggering off path and connected to the third electrode by a resistance and the third electrode being connected in series with said protective resistance and the coil of said relay to ground, and a second relay connected in series with said potentiometer and a control resistance between ground and the first 15 electrode, said first mentioned relay in released position insuring sufficient potential being impressed upon the first two mentioned electrodes 20 to trigger off said device and in operative position serving to short-circuit said control resistance and said second relay serving to short-circuit said protective resistance when potential is impressed across said potentiometer. 25
